UNITED STATES PATENT OFFICE

100,160

DESIGN FOR AN AUTOMOBILE HEATER

George R. Graff, Toledo, Ohio, assignor to
John E. Goerlich, Toledo, Ohio

Application May 11, 1936, Serial No. 62,592

Term of patent 7 years

To all whom it may concern:

Be it known that I, George R. Graff, a citizen of the United States and residing at Toledo, in the county of Lucas and State of Ohio, have invented a new, original, and ornamental Design for Automobile Heaters, of which the following is a specification, reference being had to the accompanying drawing, forming a part thereof.

In the drawing:

Figure 1 is a front elevational view of a heater showing my new design.

Figure 2 is a side elevation.

Figure 3 is a plan view.

I claim:

The ornamental design for an automobile heater substantially as shown.

Signed at Toledo, in the county of Lucas and State of Ohio, this 6th day of May, 1936.

GEORGE R. GRAFF.
